UNITED STATES PATENT OFFICE

ELLSWORTH B. OVERSHINER, OF CHICAGO, ILLINOIS, ASSIGNOR OF ONE-HALF TO
FLORENCE M. JACKSON, OF CHICAGO, ILLINOIS

ELECTRIC HEATER

Application filed January 24, 1929. Serial No. 334,639.

My invention relates to heaters of the type which are dependent upon electricity as the source of energy, and has to do more particularly with such devices which are particularly adapted for heating a room or other enclosure such as a garage, factory, shop, etc.

Modern theory and practice in heating engineering have proven that a heating device is most efficient when the heat generated thereby is directed, as by a fan or the like, in the form of a current of heated air to the point where the heat is desired, or into the room where it is required. It has been found difficult, however, to apply this principle to electric heaters for the reason that a device of this type does not begin to function efficiently until the heating coils thereof begin to glow at a substantially red heat and if a current of air is continually played upon the coils they are never permitted to attain such a degree of heat as to become efficient. The result is that the air current which is directed over the heating coils is so slightly warmed thereby that, when diluted with the cold air of the room, its effect in imparting heat to the room is negligible.

I have found that an electric heater may be made exceedingly efficient if, instead of playing a continuous stream of cold air upon the heating coils, the coils are permitted to become incandescent and a gust or stream of air then blown over or through the coil, the stream discontinued, and the cycle repeated. The time required for a coil to become heated to incandescence may be made very brief, and hence the operating cycle may be very rapid.

An object of my invention, therefore, is to provide such a heater of the electric type which will be extremely efficient, simple in construction, inexpensive to manufacture, and durable.

Another object of my invention is to provide a device of the type referred to which will furnish a series of intermittent gusts or blasts of heated air at very short intervals which, in effect, will constitute substantially a continuous current of heated air.

Many other objects and advantages of the

construction herein shown and described will be obvious to those skilled in the art from the disclosure herein given.

To this end my invention consists in the novel construction, arrangement and combination of parts herein shown and described, and more particularly pointed out in the claims.

In the drawings, wherein like reference characters indicate like or corresponding parts:

Fig. 1 shows a top plan view of a device embodying my invention;

Fig. 2 is a side elevation of the same; Fig. 3 is a front elevation of the same taken from the side opposite the motor;

Fig. 4 is a sectional view taken on the line 4—4 of Fig. 3; and

Fig. 5 is a sectional view taken on the line 5—5 of Fig. 3.

In the preferred embodiment shown in the drawings, I provide a bed plate 10 upon which is mounted a suitable bracket 11 supporting a motor 12. This motor is preferably electrical and may be of any suitable type. Attached to one end of the shaft 13 of the motor is a fan 14 and the other end of the shaft carries a worm 15 which meshes with a worm gear 16. The worm gear 16 is secured to a shaft 17 rotatably mounted in a bearing sleeve 18 which is preferably integral with a bracket 19 secured to the motor 12 and secured to the other end of the shaft 17 is a disk 21 having a cam groove 23 therein. (See Fig. 1.) This cam comprises circular dwell 23^a and a pair of radial grooves 23^b.

It will be noted from an inspection of Figs. 1 and 2 that the disk 21 has a bearing pin 25 extending axially from its hub, which pin rides in a slot 26 formed adjacent one end of a link 27. A pin 28 secured to the link 27 is slidably disposed in the cam slot 23 of the disk 21.

A casing 30 is mounted on the bed plate 10 for housing an electric heater 32. The heater 32 may be of any suitable type or arrangement, but as shown, preferably comprises a plurality of coils 33 arranged in spaced relation in a plane transverse to the direction of

flow of air from the fan 14, the coils being supported by means of plates 35 disposed at the tops and bottoms thereof. A plurality of shutters 37 are pivotally mounted in the casing 30 on opposite sides of the heating unit 32, each of the shutters 37 having an axial pin 38 disposed in suitable bearings at the top and bottom of the casing. At the top, the pins 38 are secured to levers 40. At their opposite ends, the levers 40 carry bearing pins 41 which are slidably disposed in slots 42 of a spider-like member 45. The member 45 comprises a central plate 46 (see Fig. 1) and a series of oppositely disposed arms 47 having slots 42 therein. The central plate 46 of the member 45 has a pair of longitudinal slots 48 therein which slidably engage guide pins 49 secured to the top of the casing 30.

20 A pin 50 secured to the top of the plate 46 of the member 45 slidably engages a slot 52 formed in one arm of a bell-crank lever 53 which is pivoted to the casing 30 as at 55. The other end of the bell crank lever 53 is 25 pivotally secured to the link 27 as at 56.

In the operation of the device described above, the heating unit 32 and the motor 12 are connected to a suitable source of electrical energy (not shown). Assuming that, in 30 its initial condition the shutters 37 are closed, as shown clearly in Fig. 3, the fan 14 will be functionless, inasmuch as it will merely direct a flow of air against the outside of the shutters nearest it. Hence, the coils 33 of 35 the heating unit 32 will be permitted to heat up to the glowing point. Meanwhile, the motor shaft will have been rotating the disk 21, through the worm and worm wheel constituting a speed reducing device, and the pin 40 28 of the link 27 will have been following one of the radial portions 23^b of the cam groove 23 in the disk. Hence, by the time the coils have become heated to the glowing point, the link 27 will have been moved to 45 the left (Figs. 1 and 2) by means of the cam slot 23 and the bell crank lever 53 will have been rotated on its pivot 55, moving the spider-like member 45 and the levers 40 and the shutters secured thereto. Therefore, 50 when the pin 28 is traveling in the circular dwell 23^a of the cam groove 23, the shutter 37 will be maintained for an appreciable length of time in the open position as shown in Fig. 4 and in dotted lines in Fig. 5. During this 55 time, of course, a current of air is being blown by the fan 14 through the heating coils 33 and out into the room or other points where the heat is desired. As soon as the pin 28 reaches the end of the circular dwell and follows one of the radial portions 23^b of the cam groove, the link 27 will be drawn to the right (Figs. 1 and 2) and the shutters quickly closed. The cycle will then be repeated.

It will be understood, of course, that the 60 device is so designed with respect to the cam

groove 23 and the various gearings that the shutters will be maintained in the open position just sufficiently long for the heating coils to become cooler, and that the shutters will be maintained in the closed position a sufficient length of time for the coils to become incandescent and no longer. In other words, the shutter operation will be so timed to afford the most efficiency.

It will be readily apparent that the sequence of the operations of opening and closing the shutters may be made so rapid that in effect a more or less or substantially continuous current of heated air is maintained. This construction permits smaller coils to be 75 employed with increased efficiency, and reduced cost of operation. In fact, a small heater embodying my improvements, gives more satisfactory heat at less cost than the larger heaters without my improvements. 80 It will also be apparent that the heating unit 85 32 is not necessarily restricted to an electrical device, although my invention is particularly applicable to such a type of heating unit. Other types of heaters which are 90 rapidly cooled may be substituted for the electrical heating unit shown and described, and it will be understood that I am limited to this type of heater only to the extent indicated in the appended claims.

Having thus described my invention, it is obvious that various immaterial modifications may be made in the same without departing from the spirit of my invention; hence I do not wish to be understood as limiting myself to the exact form, construction, arrangement and combination of parts herein shown and described, or uses mentioned.

What I claim as new and desire to secure by Letters Patent is:

1. In a device of the class described, a heating unit, means for projecting a current of air over said unit, and means for intermittently interrupting said current so as to permit said unit to acquire increments of heat between successive blasts.

2. In a device of the class described, a heating unit, means for projecting a current of air over said unit, and means for intermittently shielding said heating unit from 115 said air current so as to permit said unit to acquire increments of heat between successive blasts.

3. In a device of the class described, a heating unit, means for projecting a current of air over said unit, a shutter disposed between said heating unit and said air projecting means, and automatic means for intermittently opening and closing said shutter.

4. In a device of the class described, a casing, a heating unit disposed within said casing, means for projecting a current of air through said casing and over said heating unit, a movable shutter disposed on opposite sides of said casing in the path of air from 130

said projecting means, and automatic means for intermittently opening and closing said shutters simultaneously.

5. In a device of the class described, a heating unit, means for projecting a current of air over said unit, and means operated by said air projecting means for intermittently shielding said heating unit from said air current so as to permit said unit to acquire increments of heat between successive blasts.

10. In a device of the class described, a heating unit, means for projecting a current of air over said unit, a shutter disposed between said heating unit and said air projecting means, and means operated by said air projecting means for intermittently opening and closing said shutter.

15. In a device of the class described, a casing, a heating unit disposed within said casing, means for projecting a current of air through said casing and over said heating current, a movable shutter disposed on the opposite sides of said casing in the path of air from said projecting means, and means operated by said air projecting means for intermittently opening and closing said shutters simultaneously.

20. In a device of the class described, a heating unit, means for projecting a current of air over said unit, means comprising a cam and controlled by said air projecting means for intermittently shielding said unit from said air current so as to permit said unit to acquire increments of heat between successive blasts.

25. In a device of the class described, a heating unit, means for projecting a current of air over said device, a shutter disposed between said heating unit and said air projecting means, and means comprising a cam and controlled by said air projecting means for intermittently opening and closing said shutter.

30. In a device of the class described, a casing, a heating unit disposed within said casing, means for projecting a current of air through said casing and over said heating unit, a movable shutter disposed on opposite sides of said casing in the path of air from said projecting means, and means comprising a cam and controlled by said air projecting means for intermittently opening and closing said shutters simultaneously.

35. In witness whereof, I hereunto subscribe my name this 8th day of January, A. D. 1929.

ELLSWORTH B. OVERSHINER.
